UNITED STATES PATENT OFFICE

WILLIAM RIPLEY DORR, OF PALOS VERDES ESTATES, CALIFORNIA

PIPE ORGAN

Application filed May 14, 1929. Serial No. 362,895.

This invention relates to pipe organs, its object being the production of a one-manual organ which any player of a piano or a simple parlor organ can play with the same effect as if he were playing a large and expensive pipe organ having a pedalboard and a manual-to-pedal coupler.

The invention, therefore, comprises means whereby, when a single key in the bass octave of the manual is played, the corresponding pipe in the bourdon is sounded; means whereby, when a full chord is played on said bass keys, the lowest key, and it only, is caused to sound the corresponding pipe in the bourdon; means whereby, when a key in the tenor octave is played, the corresponding pipe of the bourdon is sounded; means whereby, when a full chord is played on the tenor octave keys, the lowest key, and it only, is caused to sound its corresponding pipe in the bourdon, and means whereby, when a chord is played on keys in both the bass and the tenor octaves, the Bourdon pipe corresponding to the lowest note of the chord, and it only, is sounded. These and other objects, hereinafter more fully set forth, are attained by the invention which is illustrated, principally by diagram, in the accompanying drawing. It is to be understood, however, that the drawing is intended to show merely one form in which the invention may be embodied and that the details may be widely varied without departing from the spirit of the invention. For example; whereas the controlling means are shown as a combination of electric and pneumatic instrumentalities, they may be substantially wholly electric or wholly pneumatic, or the action may be effected by any other suitable means. Therefore, the claims hereof are not to be interpreted as limited to the structures shown and described any farther than their express terms necessitate.

In the drawing, Fig. 1 is a diagrammatic view indicating portions of the manual keyboard, the manual chest and the Bourdon chest with electric circuits and operating means which are employed to control the pipes of both the manual and the Bourdon chests from the manual keyboard; Fig. 2 is a combined perspective and diagram showing

certain of the said controlling circuits and means, and Figs. 3 and 4 are diagrammatic views showing modified forms of multiple-contact switches or relays which may be employed in the system of Fig. 1.

Since the invention is concerned with the lower octaves only of the keyboard, I have indicated in Fig. 1, at K, portions only of the keyboard, the same comprising the keys of the bass octave, which are designated CC, CC#, etc.; certain of the keys of the tenor octave, which are designated C, E, etc. and one key of the middle octave, which is designated Ca. There are, of course, twelve keys in each complete octave.

In the upper right hand part of the drawing a portion of the manual chest is indicated, the action units therein, which are connected with the keys CC, DD, etc. of the bass octave, being designated CC_w, DD_w, etc.; those which are connected with the keys of the tenor octave being designated C_w, E_w, etc., while the one that is connected with the key Ca of the middle octave is designated Cax. At the left of the manual chest, the Bourdon chest is indicated. This has twelve action units which control the twelve pipes of the bourdon, the actions being designated CCC, EEE, etc. to correspond to their controlling keys CC, EE, etc. of the bass octave of the manual. As will be seen, these Bourdon chest actions may also be controlled from their corresponding keys of the tenor octave. Certain of the Bourdon pipes are indicated at PP and certain of the manual pipes at P. While I have referred to the pipes PP as "Bourdon pipes", the same may be any pipes which are customarily controlled from the pedal keyboard of an organ which is provided with pedals.

Each of the keys of the keyboard is connected, through a short conductor 3 with a lead-wire 4 which extends to a suitable source of electric current which, for purpose of illustration, is assumed to be a generator 5. The opposite pole of the generator is preferably grounded, as indicated at G. From this it will be seen that every key is charged or is alive. Associated with each key of the bass octave are four contact points, all of which are charged or made

55

60

65

70

75

80

85

90

95

100

alive when their corresponding key is played. These four points are designated 7, 8, 9 and 10. As will be noted, all of the contacts 10 are connected together in series through a conductor 11. From the contact 10 of the key BB, the conductor leads through a magnet coil 12 to ground Ga. When any one of the bass keys is played, a current flows from the source 5 to the key, to the conductor 11, through the coil 12 to the ground Ga and thence, through the frame of the organ, to ground G and to the said source. Of course, the conductor 11 could be led back to the generator, if desired; but for simplification of illustration, the various circuits are simply grounded. The coil 12 forms a part of an electro-magnetic device, the function of which will be stated hereinafter.

Extending from the contact 7 of the key CC is a wire 13 which leads through a coil 14 to a wire 15, which is grounded at Gb. Hereafter, instead of using the term "coil," I shall employ the term magnet, it being understood that the term is used in a generic sense and is intended to cover either an electro-magnet, a solenoid, or any other form of electro-magnetic device suitable for the purpose. The magnet 14 is part of an electro-magnetic device which controls a pneumatic 16. The said device and pneumatic are mounted upon a suitable board or panel 17, a portion of which is shown in Fig. 2. The pneumatic is also shown therein as being a small bellows provided with an air-supply pipe 18. This pipe is controlled by the magnet 14 so as to feed air to the pneumatic whenever the key CC is played. This air expands the bellows, causing the latter to lift a rod 19 which is connected to a switch member 20 at the upper part of the panel. As will be seen from Fig. 1, this member is elongated, the same being pivoted at its lower edge to the panel. This particular member is provided on its rear side with eleven contacts 21. These contacts are all charged or are alive, being connected with the source of current 5 through a wire 22. Any suitable form of connection may be used. As shown, the pivot rod 23, which extends throughout the length of the switch member, is connected with each of the eleven contacts 21 and also with the wire 22 which leads back to the generator 5. On the panel 17 behind each of the contacts 21 is a stationary contact 24. When the magnet 14 is energized by the operation of the key CC, its pneumatic 16 swings the switch member 20 to bring the eleven contacts 21 into engagement with their respective contacts 24, and the latter became charged.

Each of the remaining keys of the bass octave, from CC# to BB, has a corresponding magnet 14 connected with its contact 7, a corresponding pneumatic 16 and a corre-

sponding switch member 20. But, whereas the member 20 of key CC has eleven contacts 21, that of key CC# has but ten of these contacts, that of key DD has but nine, and so on, there being one contact less in each successive member until, when the last is reached, there is but one. All of these magnets, pneumatics and switch members are carried on the panel 17 and they constitute the Bourdon breaker switches. As will be shown hereinafter, other forms of multiple-contact switches accomplishing the same results may be used in lieu of those shown.

As stated, wherever one of the switch members 20 is actuated to close its contacts 21 against the contacts 24, the latter become charged. These contacts are insulated from one another, and each is connected through a conductor 25 with a magnet 26 and thence to wires 27 and 28 to ground Gb. When the upper switch member 20 is operated, all the coils 26 are energized simultaneously. It will be noted that there is no coil 26 for the key CC. The reason for this omission will be stated later. Fig. 2 shows in a somewhat more detailed manner the parts just referred to. The coil 26, as here shown, is in the form of a solenoid which, when energized, actuates its core. This core is provided with a pad-like element 29 which is adapted to close the end of an exhaust pipe leading from the pneumatic 30. The weight of the core and said element is sufficient to hold the latter closed against said pipe. When, however, the solenoid is energized, the element 29 is lifted, the air escapes from the pneumatic and the latter collapses. Whenever the wind is in the organ and the element 29 is closed against the said exhaust pipe the pneumatic is inflated, as shown, to hold a bridging contact plate 31 against two otherwise separate contacts 32 and 33. As indicated in Fig. 1, these contacts lie parallel but spaced apart, and no current can flow from one to the other except when the corresponding pneumatic is inflated. When this occurs, current flows from the source 5 through any one of the operated keys, except CC, into contact 8 of that key, through a conductor 34 to the bridged contacts 32 and 33, through another magnet 35, which is connected with the Bourdon chest, to a wire 36 leading to ground Bb through the wire 28. There are eleven of the magnets 26 and an equal number of sets of contacts 32 and 33, each set having its pneumatic 30. These elements constitute the Bourdon circuit breaker. Whenever one of the Bourdon-chest magnets is energized, the corresponding pipe of the bourdon is sounded. It will be noted that there is a circuit breaker for each action unit of the Bourdon chest except the CCC unit. Its coil 35a is connected directly with the contact 8 of the key CC through the wire 34a and is grounded through wires 36 and 28.

Each of the keys CC, DD, etc. of the bass octave is adapted, when operated to close against another contact 9. This contact is connected, through a conductor 37, to a magnet 38 of its corresponding note in the manual chest. These magnets 38 are like the magnets 35 and the magnet 35a of the Bourdon chest. They are all connected through wires 38a, 68 and 60 to ground at Gc. Whenever any one of the magnets 38 is energized, wind is admitted to the corresponding manual pipe P to sound it, if its particular stop is "on".

Sufficient description has now been given to enable the operation of this part of the invention to be understood. When a chord is played on the keys of the bass octave—say keys CC, EE and GG,—the pipes P of notes CC α , EE α and GG α of the manual chest will all sound. But it is desirable to strengthen or round out the bass by sounding the Bourdon pipe corresponding to unit CCC of the Bourdon chest. This is accomplished automatically through the contact 8 of key CC which causes magnet 35a to be energized to admit wind to the CCC Bourdon pipe. But it would never do to have the Bourdon pipes of units EEE and GGG sounding at the same time, as the resulting noise would practically drown out the higher notes of the manual-chest pipes. It is to prevent the higher notes of the chord from sounding on the Bourdon pipes that the Bourdon breaker switches and the Bourdon circuit breakers are employed. As soon as key CC is depressed, its contact 7 and magnet 14 are energized. This admits wind to the corresponding pneumatic 16, which operates the upper switch element 20, thus closing all of the eleven sets of contacts 21—24 and energizing all the magnets 26 of the Bourdon circuit breaker. This results in the instantaneous deflation of all the pneumatics 30 and the opening of all the circuits at the sets of contacts 32 and 33. Therefore, notwithstanding the energization of the contacts 8 and the wires 34 of both keys EE and GG, no current can pass across the open contacts 32 and 33 of their circuits, and the Bourdon pipes of units EEE and GGG remain silent. In this manner, therefore, all the notes of a chord struck on the bass octave keys are suppressed in the bourdon except the lowest note of the chord. At the same time, the full chord is sounded on the bass pipes of the manual chest.

Up to this point, the description has been directed to the bass-octave keys and the various instrumentalities connected with and controlled by them. The tenor octave keys will now be discussed in like manner. These keys are, as stated, designated C, E, etc., and a sufficient number of them are shown in Fig. 1 to make the various connections and operations clear.

Associated with each of these keys are five contact points. One, 7a, corresponds to the contact 7 of a bass-octave key, since it is connected, through a wire 39, to the wire 13 which leads to the corresponding contact 7. Contact 7a of key C, for example, is connected to contact 7 of key CC, with the result that the upper switch member 20 of the Bourdon breaker switches is operated to suppress all the Bourdon pipes except the one that is controlled from note CCC of the Bourdon chest. The contacts 7a of the successive keys of the tenor octave are in like manner connected with the contacts 7 of the corresponding bass-octave keys, whereby only the lowest note of a chord played on the tenor keys is sounded on the Bourdon pipes. This lowest note is sounded on these pipes, however, because of the next contact, 8a, which is connected through wire 40 to the corresponding conductor 34 or 34a of the bass-octave keys. Thus, when key C, for example, is played, current flows therefrom through contact 8a, wire 40 and conductor 34a to magnet 35a of note CCC in the Bourdon chest.

It will be noted, however, that the wires 40 are in two sections which are normally connected through a switch 41, designated on the drawing "tenor octave cut-out". Whenever the wind is turned on in the organ, this switch is closed, as indicated in Fig. 1, so as to connect the sections of the several wires 40, and the operation is as above stated. Means for so closing the switch are so well known in the art that an illustration or further description thereof is deemed unnecessary. When, however, any key of the bass octave is played, current flows from its contact 10 through the conductor 11, which connects the successive contact points 10, through the magnet 12 to ground at Ga. The energization of magnet 12 moves the cut-out switch 41 to break the circuits through all the wires 40, thus preventing all the keys of the tenor octave from sounding the Bourdon pipes. If, therefore, keys GG, BB and D, for example, be played to sound a chord on the pipes of the manual chest, key D cannot sound the Bourdon pipe DDD because its connection with the corresponding magnet 35 of the Bourdon chest is broken at the switch 41. At the same time, key BB cannot sound the Bourdon pipe BBB because key GG has operated its switch member 20 of the Bourdon breaker switches and has caused the circuit from key BB to open at the contacts 32 and 33. Therefore, when a chord is struck which is in part in the bass and in part in the tenor octave, only the lowest note of the chord can sound on the Bourdon pipes.

The next contact associated with each of the keys of the tenor octave is designated 9a. This contact is connected, through wire 42, with the magnet 38 of the corresponding

action unit of the manual chest. In the case of key C, the contact 9a is directly connected through its wire 42 to the magnet 38 of action unit C_a, so that a pipe P connected with that unit is sounded, if its stop is "on".

In playing this organ, it will frequently be very effective to couple the lowest note of a chord, when that lowest note lies in the tenor octave, to the corresponding note in the bass octave, thus reinforcing the bass note of that chord, and to have this bass coupler so operate that it couples only the lowest note so struck. That is the purpose of the instrumentalities now to be described.

One of the five contacts associated with each of the keys of the tenor octave is designated 43. This contact is at the end of a wire 44 which leads to the corresponding conductor 37 of the contacts 9 of the keys of the bass octave. When, therefore, key C of the tenor octave is played, it energizes not only magnet 38 of action unit C_a of the manual chest but the magnet 38 of note CC_a of that chest also. As in the case of the wires 40, the wires 44 are in two sections which may be connected, when desired, through a switch which is designated on the drawing "bass-coupler switch". When this switch is closed, as indicated in the drawing, and key C, for example, is depressed, the current flows from contact 43, through wire 44 and the bass-coupler switch, to the conductor 37 leading from contact 9 of key CC to the magnet 38 of note CC_a in the manual chest. The bass-coupler switch may be said to be normally open, and the circuits through wires 44 broken. The bass-coupler switch is closed by a magnet 45 in an electric circuit which extends from the conductor 4, shown below the keyboard, through wires 46 and 47, a switch 48, a wire 49 to the magnet, and thence through a wire 50, a switch 51 and wire 52 to ground Gc. The switch 48 is manually controlled through the bass-coupler stop 53. When that stop is drawn, the circuit is closed at the switch 48 and the magnet 45 is energized to close the bass-coupler switch. The switch 51 is normally closed but is opened by a magnet 54 in a wire 55 which is connected with the wire 11 having the series of contacts 10 associated with the bass-octave keys. When any one of these keys is depressed it not only opens the tenor-octave cut-out switch but also opens the switch 51, thus de-energizing the magnet 45 and permitting the bass-coupler switch to open notwithstanding the bass-coupler stop 53 remains drawn. As soon as the key is released, however, the switch 51 automatically closes again, thus re-establishing the circuit through the magnet 45 and again closing the bass-coupler switch.

While, by the means thus described, the lowest note of a chord struck on the tenor octave keys is coupled to the corresponding pipe in the bass octave of the manual chest, it is

highly desirable that all the other notes of the chord be suppressed in said bass octave. This cut-out of the higher notes is effected through instrumentalities similar to those described for suppressing the higher notes of a chord struck on the keys of the bass octave. When depressed, the key E, for example, closes against its fifth contact, designated 56. This contact is connected through a conductor 57, with a magnet 58. Current flows from the key through the said magnet and thence, through wires 59 and 60, to ground Gc. The energization of the magnet 58 rocks a multiple contact switch or relay 61 through a very short arc. This switch, like the switch member 20 of key EE, has seven closely-spaced contacts 62 projecting from its perimeter. When the switch is closed by the magnet 58, all its contacts are closed against contacts 63. As shown more clearly in Fig. 3, the contacts 62 are all electrically connected to the central axis 64 of the switch, which axis is connected, through wires 65, 46 and 4, to the source 5 of electric current. There are also seven of the cooperating contacts 63 for the key E which are connected to their respective magnets 66 in the bass-coupler circuit breaker, 67, these magnets being connected with a wire 68, which leads to wire 60 and thence to ground Gc. The bass-coupler circuit breaker is substantially identical with the Bourdon circuit breaker.

While the complete system will include eleven of the multiple switches 61, but one of them is shown, that one corresponding to key E. They are all alike, except as to their numbers of contacts 62. As in the Bourdon breaker switches, the switch operated from key C would have eleven contacts, the one operated from key C# would have ten contacts, and so on, the number of contacts diminishing progressively until the switch controlled from key B would have but a single contact.

The multiple-contact switches 61 may be operated directly from their respective magnets 58, as indicated in Fig. 1, or they may be operated pneumatically, as in Fig. 3, the pneumatics 69, in that case, being controlled by the magnets 58, as are the pneumatics 30 of Fig. 2. The switch 61 of Fig. 3 is provided with eleven contacts 62, being thus adapted for use with key C of the tenor octave, or with key CC of the bass octave.

In Fig. 4 I have shown a modified form of multiple-contact switch or relay which may be substituted for the type of switch shown at 61 or at 20 in Fig. 1. These various forms of switches perform, or are adapted to perform, the same functions and any of these forms may be used. In Fig. 4, a small pneumatic 70 is controlled by a magnet 71. When the latter is energized, it causes the pneumatic to be deflated. This pneumatic carries a bridging plate 72 which, when the pneumatic is inflated, closes against a series of

70

75

80

85

90

95

100

105

110

115

120

125

130

contacts 73 to establish electric connection between them, as in Fig. 2. When the pneumatic is deflated this connection is broken.

The depression of key E, for example, that being the key with which the only switch 61 shown is connected, causes its magnet 58 to operate its said switch 61, with the result that all the magnets 66 of the keys above E in the tenor octave are energized to prevent any of the latter keys from sounding their respective manual pipes of the bass octave. In this connection, it will be understood that each of the magnets 66 controls a pneumatic, like pneumatic 30 of Fig. 2, and that these pneumatics control their respective contacts to make or break circuits leading to the magnets 38 of the notes EE α , GG α , etc. of the bass pipes of the manual chest. Thus, if key E be played, its magnet 38 of note E α will be energized to cause a pipe P of that note to sound and, at the same time, its magnet 58 will be energized to operate its multiple-contact switch 61. This will result in the energization of all the magnets 66 of the bass-coupler circuit-breaker which control the circuits leading to the note FF α and those higher in the bass octave in the manual chest, thus preventing any of the pipes of these notes from sounding. As shown in Fig. 1, the contact 43 of key E is connected, through wire 74 and the bass-coupler switch, to contacts at 75 and 76. The latter contact is connected, through a wire 77 to the conductor 37 which leads to the magnet 38 of note EE α . Contact 56 over key E, leads to magnet 58 operating switch 61 controlling circuit breaker for note FF α and all higher notes of bass octave. The depression of key E, therefore, results in the deflation of the pneumatic controlling the contacts 75 and 76 shown, opening the circuit leading to note FF α and preventing the manual pipes of that note from sounding. Through similar circuits and means controlled by the switch 61 of key E and comprising contacts 62 and 63, all the other manual pipes in the bass octave above that of FF α are prevented from sounding.

Having thus described my invention what I claim as new and desire to secure by Letters-Patent is:—

1. In a pipe organ, the combination with a manual keyboard comprising bass octave and tenor octave keys, of a series of manual pipes corresponding to and operatively connected with the keys of said keyboard, and of a set of Bourdon pipes corresponding to the keys of the bass octave of said keyboard, and means operatively connected with each of the keys of the bass and tenor octaves for causing its corresponding Bourdon pipe to sound when the key is played and for preventing any other Bourdon pipe which is higher in the scale from sounding at the same time.

2. In a pipe organ, the combination with a

manual key board comprising bass octave and tenor octave keys, of a series of manual pipes corresponding to and operatively connected with the keys of said keyboard, of a set of Bourdon pipes corresponding to the keys of the bass octave of said keyboard, and electromagnetic means operatively connected with each of the keys of the bass and tenor octaves for causing its corresponding Bourdon pipe to sound when the key is played and for preventing any other Bourdon pipe which is higher in the scale from sounding at the same time.

3. In a pipe organ, the combination with a manual keyboard comprising base octave and tenor octave keys, of a series of manual pipes corresponding to and operatively connected with the keys of said keyboard, of a set of Bourdon pipes corresponding to the keys of the bass octave of said keyboard, means operatively connected with each of the keys of the tenor octave for causing its corresponding Bourdon pipe to sound when the key is played, and means operatively connected with each of the keys of the bass octave for preventing any of the keys of the tenor octave from playing its corresponding Bourdon pipe when any key of the bass octave is played at the same time.

4. In a pipe organ, the combination with a manual keyboard comprising bass octave and tenor octave keys, of a series of manual pipes corresponding to and operatively connected with the keys of said keyboard, and of a set of Bourdon pipes corresponding to the keys of the bass octave of said keyboard, means operatively connected with each of the keys of the tenor octave for causing its corresponding Bourdon pipe to sound when the key is played, and electro-magnetic means operatively connected with each of the keys of the bass octave for preventing any of the keys of the tenor octave from playing its corresponding Bourdon pipe when any key of the bass octave is played at the same time.

5. In a pipe organ, the combination with a manual keyboard comprising bass octave and tenor octave keys, of a series of manual pipes corresponding to and operatively connected with the keys of said keyboard, and of a set of Bourdon pipes corresponding to the keys of the base octave of said keyboard, and means operatively connected with the keys of both the bass octave and tenor octave whereby, when a chord is sounded upon the keys of both octaves, only the lowest note of the chord is sounded upon the Bourdon pipes.

6. In a pipe organ, the combination with a manual keyboard comprising bass octave and tenor octave keys, of a series of manual pipes corresponding to and operatively connected with the keys of said keyboard, a set of Bourdon pipes corresponding to the keys

of the bass octave of said keyboard, and electro-magnetic means operatively connected with the keys of both the bass octave and tenor octave whereby, when a chord is sounded upon the keys of both octaves, only the lowest note of the chord is sounded upon the Bourdon pipes.

7. In a pipe organ, the combination with a manual keyboard comprising bass-octave and tenor-octave keys, of manual pipes corresponding to said keys, means whereby the said pipes are caused to sound when their corresponding keys are played, a second series of pipes corresponding to the keys of the bass-octave, means for causing any one of the latter pipes to sound when its corresponding key of the bass-octave is played, means under control of the played key for preventing any other pipe of the second series which is higher in the scale from sounding at the same time, electric connections between the keys of the tenor-octave and the corresponding pipes of the second series through which said latter pipes may be caused to sound when the corresponding key of the tenor-octave is played, said connections comprising a normally closed multi-contact switch, and means under control of all the keys of the bass-octave for causing the said switch to open its contacts when any key of the bass-octave is played, whereby, when a chord is played on the bass-octave and tenor-octave keys, only the lowest note of the chord is sounded on the pipes of the second series.

8. In a pipe organ, the combination with a manual keyboard comprising bass-octave and tenor-octave keys, of manual pipes corresponding to said keys, means whereby the said pipes are caused to sound when their corresponding keys are played, a series of Bourdon pipes corresponding to the keys of the bass-octave, means for causing any one of the Bourdon pipes to sound when its corresponding key in the bass-octave is played, means under control of the played key for preventing any other of the Bourdon pipes which is higher in the scale from sounding at the same time, electric connections between the keys of the tenor-octave and the corresponding Bourdon pipes through which said latter pipes may be caused to sound when the corresponding key of the tenor-octave is played, said connections comprising a normally closed multi-contact switch, and means under control of all the keys of the bass-octave for causing the said switch to open its contacts when any key of the bass-octave is played, whereby, when a chord is played on the bass-octave and tenor-octave keys, only the lowest note of the chord is sounded on the Bourdon pipes.

9. In an organ, the combination of a keyboard comprising bass-octave and higher-octave keys, manual pipes corresponding to the respective keys of the keyboard, means con-

necting the keys with their respective pipes for causing the latter to sound under normal conditions when their respective keys are played, and means under control of the keys of the bass-octave for preventing all pipes of the bass-octave from sounding when a chord is struck on the keyboard except the lowest note of said chord.

10. In an organ, the combination of a keyboard comprising bass-octave and higher-octave keys, manual pipes corresponding to the respective keys of the keyboard, means connecting the keys with their respective pipes for causing the latter to sound under normal conditions when their respective keys are played, and electro-magnetic means under control of the keys of the bass-octave for preventing all pipes of the bass-octave from sounding when a chord is struck on the keyboard except the lowest note of said chord.

11. In a pipe organ, a keyboard comprising bass-octave and tenor-octave keys, manual pipes corresponding to the respective keys of the keyboard, means connecting the keys with their respective pipes for causing the latter to sound under normal conditions when their respective keys are played, electric connections between the tenor-octave keys and the corresponding pipes of the bass-octave, said connections comprising a multi-contact bass-coupler switch, a bass-coupler stop for causing the said switch to close when the said stop is operated, and means under control of the bass-octave keys for causing said bass-coupler switch to open whenever a key in the bass-octave is played, whereby, when a chord is sounded on the tenor octave keys, only the lowest note of said chord will be sounded upon the pipes corresponding to the keys of the bass-octave.

In testimony whereof I have signed my name to this specification.

WILLIAM RIPLEY DORR.
